TOP SPINNING DEVICE

Emmitt B. Thigpen, Macon, Ga., assignor of one-fourth to Wylie A. Mason, and one-fourth to John W. Douglas, Bibb County, Ga.

Application April 8, 1938, Serial No. 200,981

1 Claim. (Cl. 46—69)

This invention relates to top spinning devices, and its general object is to provide a device of that character which is capable of spinning a top with minimum effort on the part of the user, as well as to cause the top to spin for a longer period of time than is possible by the use of a cord now generally employed for that purpose, in that my spinning device includes a spring to be wound for storing up energy, with rotatable housing means for and driven by the spring, and to which the top is detachably associated to be spun thereby and ejected therefrom.

A further object is to provide a top spinning device in the form of a pistol, to add to the fun and amusement of spinning the top, in that the device includes a handled supporting means of pistol formation having trigger actuating mechanism therein for releasing the spring means, so that the top is ejected or shot from the spinning means.

Another object is to provide a top which can be spun by a cord in the usual manner, if desired, but my device enables the user to have a number of tops spinning at the same time, due to the fact that the tops can be easily and expeditiously spun thereby.

A further object is to provide a top and spinning device therefor that are simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:

Figure 1 is a longitudinal sectional view taken through the spinning device which forms the subject matter of the present invention, and illustrates a top applied thereto, the top being broken away and in section.

Figure 2 is a side elevation of the spinning device and top.

Figure 3 is a rear view of the spring actuated rotating or spinning means.

Figure 4 is a vertical sectional view taken therethrough.

Figure 5 is a front view of the spinning means that includes holding and releasing pins for the top.

Figure 6 is a sectional view taken approximately on line 6—6 of Figure 5.

Figure 7 is a vertical sectional view taken through a modified form of spinning means.

Referring to the drawing in detail, it will be noted that the handled supporting means of my spinning device is in the form of a pistol in that it includes a barrel 1, a handle 2 and a trigger guard 3. The supporting means is hollow, and is preferably made into a pair of like sections secured together by any suitable means, such as screws 4.

Fixed in the outer end of the barrel 1 is a plug 5 having a central opening therein, through which extends a shaft 6, the latter being secured in the barrel by a pin 7 and extends a considerable distance therefrom, as best shown in Figure 1.

The outer portion of the shaft 6 has formed on or otherwise secured thereto a collar 8 and rotatably mounted on the shaft 6 and held accordingly by the collar, is a relatively flat cylindrical housing 9 having a flat coiled spring 10 therein, coiled about the collar 8 with the outer end of the spring fixed to the cylindrical wall of the housing 9 by a rivet or the like 11. In Figure 4 it will be noted that the inner end of the spring 10 is associated with the collar 8, by an arcuate strip 12 which is preferably a piece of the leaf spring cut therefrom and arranged to provide a channel for receiving the inner end of the spring 10, as shown.

In the modified form of Figure 7, it will be noted that the collar 8 is provided with a notch 13, with the inner end of the spring 10 mounted in the notch. However, the inner end of the spring may be associated with the collar by any suitable means, providing it is not fixed thereto, as a loose connection with the collar is necessary in order to prevent the spring from breaking on the recoil thereof.

The cylindrical wall of the housing preferably has an annular flange formed thereon and extending outwardly therefrom for the purpose of receiving a channel bead 14 formed about the outer edge of the front wall of the housing, for securing the front wall in place, as will be apparent, and fixed to the front wall and extending forwardly therefrom are oppositely inclined studs 15 for a purpose which will be later described, together with that portion 16 of the shaft that extends outwardly from the housing.

The hollow handled supporting means has pivotally mounted therein a trigger mechanism which includes a ring member 17 pivoted as at 18, and extending laterally from the ring mem-

ber 17 is a stud 19 for receiving one end of a leaf spring 20 that is coiled about the pivot 18, with the opposite end engaging the upper wall of the body of the supporting means, as shown in Figure 1. Formed on the ring member 17 and extending from the periphery thereof is a trigger handle 21 arranged for movement within the trigger guard 3 and for that purpose, the body is slotted as at 22 for movement of the ring member therein.

Pivots secured to the ring member and extending forwardly therefrom is a holding and releasing lever 23 for the spinning means, and which is received in any one of a number of openings 24 in the rear wall of the housing 9, for holding the spinning means against rotation, after the spring has been wound for storing up energy therein. The lever 23 extends through an opening in the plug to be guided and supported thereby.

The top which is indicated by the reference numeral 25 is of special construction, in that it includes a disk-shaped head 26. However, the body is of the usual conical formation with a plug 27 mounted in and secured to the apex portion thereof, as shown. The disk-shaped head 26 is provided with a flat outer face for engagement with the outer wall of the housing 9, and has a bore 27' centrally arranged therein for the purpose of receiving the extending portion 16 of the shaft. The head 26 is likewise provided with a pair of holes 28 disposed upon opposite sides of the bore 27', for receiving the studs 15 and the holes 28 are inclined to the same degree as the studs, for fitting association of the latter therein, as will be apparent.

In the use of my toy or spinning device, it will be obvious that the trigger is moved against the action of the leaf spring 20 for moving the lever 23 out of an opening 24, thence the housing is rotated for winding the spring 10 to store up energy therein. When the spring is completely wound, the trigger is released to allow the lever 23 to again be disposed in one of the openings 24 for holding the housing against rotation. The top is then applied to the studs 15 and portion 16 of the shaft, as shown in Figure 1, with the result it will be apparent that when the trigger is pulled at this time, the housing is released from the lever 23, and caused to rotate by the spring 10. Such action will of course rotate or spin the

top 25 and eject or shoot the same from the studs 15 and portion 16 of the shaft.

While I have illustrated a top of a special construction, a top of the usual construction can be spun by my device, merely by providing the bore 27' and the holes 28 in the upper end thereof.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:

A top spinning device comprising handled supporting means in the form of a pistol including a handle and a barrel, a shaft secured in and extending from the outer end of the barrel, a notched collar secured to the inner end of the extending portion of the shaft, a flat cylindrical housing rotatably mounted on the shaft about the collar and held by the latter, a flat coiled spring within the housing and wound about the collar, said spring having its outer end secured to the cylindrical wall of the housing and its inner end mounted in the notch of the collar for loose association therewith, whereby upon rotation of the housing in one direction the spring will be wound to store up energy therein for rotating the housing in an opposite direction, diametrically opposed studs extending from the outer wall of the housing and inclined in opposite directions with respect to each other, a top including a head provided with a flat face engageable with the outer wall of the housing, said head having holes therein to fittingly receive the studs and a bore to receive the extending portion of the shaft for detachably securing the top to the housing to be ejected therefrom upon rotation thereof by the spring, said housing having openings in the inner wall thereof, and means within and movable through the barrel to be received in any one of the openings of the housing for holding the latter against rotation, and spring pressed trigger means mounted in the supporting means and having the holding means pivotally connected thereto for actuating the same.

EMMITT B. THIGPEN.
